[57] CLAIM

The ornamental design for a moth eliminator or the like,
as shown and described.

DESCRIPTION

FIG. 1 is a top, front perspective view of a moth eliminator or the like, showing my new design;

FIG. 2 is a rear elevational view thereof;

FIG. 3 is a bottom plan view thereof; and

FIG. 4 is a side elevational view, the opposite side being a mirror image thereof.

The broken line showings of a fence, light bulb, and light bulb socket are for illustrative purposes only and form no part of claimed design.
